Primary Examiner — Jonathan J Han*Assistant Examiner* — Amanda J Berlinski(57) **CLAIM**

The ornamental design for an oral irrigator and charging base assembly, as shown and described.

DESCRIPTION

FIG. 1 is an exploded front and top perspective view of an oral irrigator and charging base assembly, showing my new design;

FIG. 2 is an exploded rear and bottom perspective view thereof;

FIG. 3 is an exploded front elevation view thereof;

FIG. 4 is an exploded rear elevation view thereof;

FIG. 5 is an exploded left side elevation view thereof;

FIG. 6 is an exploded right side elevation view thereof;

FIG. 7 is a top plan view thereof; and,

FIG. 8 is a bottom plan view thereof.

The broken lines in the figures illustrate portions of the oral irrigator and charging base assembly that form no part of the claimed design.

1 Claim, 8 Drawing Sheets(56)
